REDUCED RECOIL TYPE GUN

Charles Dennistoun Burney, Baynards Park,
near Cranleigh, EnglandApplication September 1, 1944, Serial No. 552,347
In Great Britain December 5, 1941Section 1, Public Law 690, August 8, 1946
Patent expires December 5, 1961

7 Claims. (Cl. 89—1.7)

2

1
The present invention relates to ordnance and small arms, and has for its object to eliminate the recoil of the gun on firing, thereby enabling the firearm to be discharged from the shoulder, using heavy projectiles, without discomfort or injury to the firer, or enabling artillery or naval guns to be fired from very light mountings and with a minimum of stress upon the deck or hull.

Attempts have already been made to reduce the recoil of guns by rearward discharge of the chamber gases to produce a forward reaction acting against the rearward kick of the barrel, with varying degrees of success. For example, it has been proposed to provide, at the muzzle end of the gun, deflector surfaces for the gases issuing from the muzzle, which reverse the direction of motion of the gases and cause a reaction which opposes recoil of the gun barrel. It has also been proposed in the case of trunnion mounted guns to allow the gases of combustion, after passing for a short distance down the barrel, to discharge through the trunnions in a rearward direction, thus producing a forward reaction opposing the recoil of the barrel. With both of these arrangements, however, only a relatively small proportion of the recoil shock is absorbed. By means of the present invention, however, any proportion, up to 100 per cent of the recoil shock can be absorbed, according to requirements.

Also it has been proposed to provide expanding passages in the rear wall of the breech block adjacent to the base of the cartridge to permit rearward escape of the chamber gases on firing into an outwardly flared deflector for the purpose of reducing or eliminating the recoil of the gun.

Furthermore it has been proposed to construct a gun with an explosion chamber, an expansion nozzle between the said chamber and the gun barrel, a chamber or space behind the projectile into which said nozzle opens, and a passage or passages extending from said space to the outside of the gun, which is or are directed outwardly and rearwardly.

Guns according to the present invention are distinguished from the prior art in regard to the construction of the breech end of the gun, and according to one feature of the invention there is an extension in rear of the cartridge chamber, formed by a breech chamber which provides a space between the space occupied by the cartridge and one or more rearwardly directed gas nozzles or outlets at the rear end of the breech chamber.

The invention includes guns having a cartridge chamber forming a co-axial rearward extension of the gun barrel, and co-axially in rear of the cartridge chamber a free space communicating with the atmosphere through one or more rearwardly directed nozzles or gas outlets, and it also includes guns having a free space co-axially behind the projectile which communicates with the atmosphere through one or more rearwardly directed nozzles or outlets, and a cartridge chamber disposed laterally of the axis of the gun and communicating with said space.

In conformity with the foregoing, according to the invention, the improved gun may have a breech which includes a cartridge chamber or space, and a gas storage chamber or space which constitutes an enlargement or extension of the breech chamber and is open to the atmosphere through one or more rearwardly directed gas discharge nozzles, through which the gases discharge to the atmosphere.

Furthermore the cartridge chamber at the rear end of the gun may be closed by a movable breech block which contains a gas chamber adapted to form an extension or enlargement of the cartridge chamber, said breech block having one or more rearwardly directed gas discharge nozzles or outlets communicating with said gas chamber.

From the foregoing it will be appreciated that a gun according to the invention is, in effect, an open ended tube, with the projectile and the propelling charge loaded into it at a medial point in its length. When fixed ammunition is used, the cartridge case, instead of having a closed base with the firing cap in the centre thereof, has an open base, and is of rim fire type. Provision may be made to cover the open base of the cartridge with some material which will make the cartridge water-tight, but will easily be shattered and consumed on firing, to avoid choking the nozzle.

The open ended tube or barrel is made up of two parts viz. a rearward extension or breech portion, and the front part or barrel proper, with the cartridge chamber. The rear or breech contains a gas chamber and is fitted with one or more rearwardly directed gas discharge nozzles, said breech part being movable in relation to the front part, to permit insertion of the projectile and cartridge into the front part, whereafter the rear part is closed on the base of the cartridge to grip the rim of the cartridge between the two barrel portions.

Instead of absorbing the whole recoil of the gun by gas reaction of the chamber gases, part

of the recoil may be absorbed by gas reaction and part by the gun mounting. In this connection the gun may be loaded with two charges, one of which is of quick burning type for propulsion of the projectile, and the other of a slow burning type, which remains active in retarding the recoil of the barrel after the projectile has left the gun muzzle.

It may be found desirable in the larger types of gun to take up part of the recoil on the gun mounting by using a firing charge less than that necessary to balance the recoil shock entirely, in order to reduce the back blast of the recoil resisting gases to a reasonable extent. Further, in the case of small arms, even when the charge required to absorb the whole of the recoil is small enough to produce a reasonable back blast, it may, nevertheless, be found desirable to use a charge less than that required to absorb the whole recoil shock so as to retain a certain amount of barrel recoil, in order to operate mechanism, such as automatic reloading mechanism, in the case of small arms of the automatic or machine gun type.

It will be understood that the invention as described above involves the use of a greatly augmented charge of propellant, i. e. a charge several times the maximum which could be safely used in a gun of given calibre if operating with a closed chamber, and the bulk of the gases developed by combustion of the propellant are discharged through the nozzles. Thus the cartridge chamber must be considerably larger than that of a standard gun of equal power in order to produce the same muzzle velocity whilst allowing at least 50% or more of the gases produced to be discharged through the nozzles.

The exact proportion of the gases thus discharged rearwardly will depend upon the extent to which it is desired that the recoil be absorbed, and the proportion will depend upon the area of the nozzle or the sum of the nozzle areas, in relation to the bore area of the gun barrel.

For the complete elimination of the recoil it has been found, for example, that in one type of gun the nozzle area should be substantially 66% of the barrel cross-sectional area, in which case about six times the volume of gases is discharged through the nozzles than is discharged through the barrel.

In most cases the gun will be designed to produce either complete recoil elimination or balance of a fixed percentage of recoil, leaving the balance of recoil for the operation of automatic unloading and loading gear, or the like, as in automatic or machine guns. In some cases, however, it may be desired to vary the amount of recoil energy absorbed, and in these circumstances means may be provided for blocking a proportion of the nozzles in symmetrically disposed pairs, or in the case of a central nozzle for varying its effective area by means of a pointed valve member adjustably mounted in the nozzle.

According to another feature of the present invention, a grid or perforated screen may be provided between the chamber space to be occupied by the propellant charge and the nozzles, to serve the dual purpose of preventing ejection of unconsumed propellant through the nozzles and maintaining a free space through which the propellant gases may pass to the nozzle or nozzles. Preferably the grid or screen is in the form of cage-like member having slotted or perforated walls which change the direction of the gas flow

but resist passage of any solid particles of propellant. The said member may, for example, be in the form of a truncated cone mounted in the breech portion of the gun, which carries the nozzles and contains the chamber in which the grid or screen member is mounted, with its narrow end towards the propellant when loaded in the chamber space at the rear end of the gun barrel proper.

In carrying the invention into practice the gun chamber may comprise two sections, one of which receives the propellant and the other of which contains a grid or equivalent member separating the charge from the nozzles and forming a space permitting free access of the gases to the nozzles from all directions. The first section may conveniently be provided as a rearward extension of the barrel structure, whilst the second section may be embodied in a breech member, separable from the barrel structure, to permit loading of the projectile and propellant charge into the barrel and chamber respectively. The breech section may consist of a casing open at its front end and enclosing a chamber containing a grid or cage, which may be of truncated cone shape, with its narrow end towards the barrel and its inclined walls perforated or saw cut. The rear wall of the breech casing is formed by a nozzle plate having one or more outwardly flared nozzles formed therein, or apertured to receive the root ends of one or more external expansion nozzles. There may be a single axial nozzle, or a symmetrical ring of nozzles, or both.

The cartridge chamber proper or space containing the propellant will normally be of larger diameter than the gun barrel, and the grid chamber or free gas space may be of equal diameter to, or of larger diameter than, the cartridge chamber, so that the nozzle plate will be of ample size to accommodate a number of nozzles having a total throat area equal to 66% of the barrel bore area. With this arrangement, it will be obvious that the venting area between the cartridge space and the gas space in which the grid is located is at least equal to the cross-sectional area of the barrel, so that the gases can escape not less freely through the gas space than along the barrel bore.

For reasons of stability, particularly when self-propelled projectiles are used, it may be necessary to destroy the pressure of the gases on the base of the projectile before it leaves the muzzle. To achieve this end, at a suitable distance from the end of the muzzle, the barrel may, in known manner, be perforated to allow lateral escape of the gases, either directly into the atmosphere, or into a surrounding casing open at its forward end surrounding the muzzle end of the gun. The sudden increase of the barrel volume when the projectile passes the perforations will cause a sudden drop in the chamber pressure to such an extent that the combustion of the propellant charge is very slow, or may even be brought to an end before the charge is fully burnt, so that the pressure acting on the projectile on leaving the gun muzzle may be entirely eliminated.

In order that the invention may be clearly understood and readily carried into practice, examples of small arms and ordnance constructed in accordance therewith are illustrated by way of example in the accompanying drawings, in which:

Figures 1 to 7 illustrate a 1.9" anti-tank rifle according to the invention:

Figure 1 is a longitudinal section of the front portion of the rifle.

Figure 2 is a longitudinal section of the rear portion.

Figure 3 is an end elevation with the breech closed and the gas discharge nozzle removed.

Figure 4 is an end elevation with the breech open, part being broken away.

Figure 5 is an end elevation with the breech chamber removed and partly in section.

Figure 6 is a detail view to a larger scale of the firing mechanism, and

Figure 7 is a detail view of the extractor mechanism;

Figure 8 is a diagram showing a modified construction of recoilless gun in regard to the disposition of the cartridge chamber,

Figure 9 is detail view of the breech and firing mechanism of a 3 1/2" low velocity recoilless gun according to the invention.

Figures 10, 11 and 12 are detail views of the extractor mechanism of Fig. 9, Figures 11 and 12 showing the positions of the parts with the breech closed and open respectively,

Figure 13 shows a 3.45", 25 pounder recoilless field gun in accordance with the invention,

Figure 14 is a detail view showing the breech block in the open position.

Figure 15 is a view of the breech block to a larger scale showing the locking mechanism and the extractor mechanism, and

Figure 16 is a detail view of one of the breech trunnions.

Figures 1 to 7 of the drawings illustrate a construction of 1.9" recoilless gun according to the invention, intended for use mainly as an anti-tank rifle and designed for use as a shoulder weapon.

The barrel consists of a steel tube 1 which may have a smooth, but preferably has a rifled bore. On the rear end of the barrel 1 is mounted the cartridge chamber 2, to which is connected the breech block or member containing chamber 3, which is rotatably supported in a cradle or frame 4 pivoted to the cartridge chamber 2 at 5. The rear end of the chamber 3 has an opening which is covered over within the chamber 3 by a perforated cage or grid 6 which supports in its interior an adjustable valve member 8 which can be screwed in or out to regulate the effective size of the gas discharge opening in the end of the chamber 3. The said opening is fitted externally with a gas discharge nozzle or funnel 7 which prevents undue spread of the discharge gases.

The breech block 3 is adapted to be rotated in its cradle or carrier 4 by a handle 9, and it has an interrupted screw-thread engagement with the mouth of the cartridge chamber 2. The handle 9 is provided with a locking catch 10 and when this is operated the breech block 3 can be rotated in the cradle 4 into a position in which the interrupted threads are disengaged, thus permitting the breech chamber to be opened by angular movement of the block 3 away from the cartridge chamber 2 into the position shown in Figure 4.

The forward part of the barrel carries a pistol grip 11 with which is associated a trigger 12, 70 having a safety catch 12a, and pressure on the trigger pulls the wire 13 connected at the breech of the gun to the firing mechanism. A short distance in rear of the grip 11 is a curved shoulder rest 14, which is located at such a point

that the C.G. of the gun lies vertically above its resting point on the shoulder. This is an important feature of design in regard to rendering the gun easy to handle and control, which becomes a difficult matter in the case of a heavy gun if the bulk of the weight is forward of the shoulder. The location of the shoulder rest 14, therefore, has an important effect on the manoeuvrability of the gun.

10 The wire 13 passes along beneath the barrel and inside a metal cover plate 15, and at its breech end is attached to a pivoted lever 16.

The lever 16 (see Figure 6) has a nose 17 adapted, when lever 16 is rocked by a pull on wire 13, to strike a pin 18 on a pivoted catch lever 19 having its tail pressed downwardly by a spring 20 and its nose 21 engaged with the head 22 of the firing rod 23, when the firing mechanism is cocked (as shown). The rod 23 carries a nut

20 24 and is surrounded in a casing 13a by a spring 25 bearing between a fixed shoulder and the nut 24. When the firing rod 23 is released by depression of the catch lever 19 by pivoted lever 16, the rod 23 flies rearwards under the pressure of 25 spring 25 and in so doing its head 22 strikes the end of the pivoted lever 26, the other end of which is engaged with the end of a firing pin 27 whose nose 28 is located opposite to the percussion cap of the cartridge loaded into the chamber 2 of the gun.

The rocking lever 16 also has another arm having a nose 29, which enters a recess or notch 30 in the breech block 3 when the lever rocks to release the firing pin 27, so that at the moment 35 of firing the breech block 3 is positively locked against rotation in cradle 4, additionally to the lock provided by handle catch 10.

The firing rod 23 is automatically moved forwardly into its cocked position shown in Figure 40 2 by the opening of the breech into the position shown in Figure 4. This is accomplished by means of a U-shaped stirrup member 23b the arms of which are pivoted at 23a to the breech end of the barrel structure, whilst the rear end 45 of said member 23b (Fig. 6) passes round the rear end of firing rod 23. When firing has taken place the rod 23 moves back into contact with the loop of stirrup member 23b and as the breech is 50 opened is pulled forwardly in relation to the breech block until the nose 21 on lever 19 re-engages behind the head 22 of rod 23. The firing rod 23 can be held against rearward movement by a pivoted safety catch 23c (Fig. 2).

55 The extractor mechanism is, for the sake of clearness, not shown in Figures 2 and 6, but is shown in Figure 4, and in detail in Figure 7. In a recess in the edge of the cartridge chamber, which comes beneath the rim of the cartridge case, is a part circular extractor fork 31 mounted on two short arms 36 pivoted about axis 32. The hub portions of said arms 36 have projecting noses 33, which are engaged by the ends of curved levers 34. The levers 34 rotate about axis 5 supported by lugs 35 on the cartridge chamber 2, and the breech carrier 4 also rotates about said axis 5, on which it is pivoted by means of arms 37. On the outer sides of the hub-portions of levers 34 are teeth 38, whilst on the inner sides of arms 37 are co-operating abutments, which when the breech is fully opened strike against teeth 38 and thus suddenly rotate said levers, so that their noses, by their engagement with the noses 33 on the extractor levers 36, cause a sudden movement of the extractor 31 out of its recess,

whereby the cartridge case is forcibly dislodged from the cartridge chamber 2.

From the foregoing general description of the invention it will be appreciated that the propelling charge is ignited in chamber 2, and this is freely open to the atmosphere through the chamber 3 and its discharge opening through grid 6 and funnel member 7. As will be apparent from Figure 2, the gases developed by combustion of the charge in cartridge space 2 are free to expand or vent into the space 3 through an opening which is somewhat larger in area than the forward end of the cartridge space and the rear end of the barrel. The grid 6 serves to prevent any of the propelling charge being blown out of chamber 3 in an unburnt condition, and also to maintain a clear space over the discharge opening of said chamber, allowing free access of the gases to said opening.

The extent to which the barrel recoil is eliminated will depend upon the relative areas of the discharge opening of chamber 3 and the barrel cross-sectional area, and this relation can be controlled by adjustment of valve 8 which can be adjusted by a tool, such as a turn screw, through funnel member 7. If the valve 8 is adjusted so that the effective area of the gas discharge opening is substantially 66% of the barrel cross-section, then the barrel recoil will be substantially completely eliminated. In the present case since the gun is designed for use as a shoulder weapon the valve 8 would be adjusted to give complete elimination of recoil, but if the gun were adapted to operate as a machine gun it would be supported on a mounting and the valve 8 adjusted to allow sufficient barrel recoil to operate the necessary automatic loading and firing mechanism.

By throttling down the gas discharge opening the barrel recoil will be increased, but at the same time the chamber pressure operative on the bullet will be increased, so that a higher muzzle velocity and greater range or penetrating power of the bullet will result, whereby a degree of flexibility in the tactical power of the gun is obtainable if desired.

In some cases, for considerations of stability of the projectile, the muzzle portion of the gun may be perforated in known manner for a short length, so that the gases following the projectile may leak off to any desired extent before the projectile leaves the muzzle. By this means the gas pressure on the base of the projectile may be gradually destroyed before it leaves the muzzle. This perforated length of the barrel is preferably surrounded by a conical or tapering casing 98, open at its forward end surrounding the muzzle. By way of example the barrel perforations may be of a total area four times the area of the barrel bore, and the maximum area of the annular space between the gun muzzle and the conical casing may be twice the bore area.

It will be found that the perforation of the muzzle will produce a forward reaction on the barrel tending to counteract the recoil, so that if this was fully balanced by making the nozzle area 66% of the bore area the gun will, on firing, tend to move forwardly in the same direction as the projectile. Consequently if muzzle perforation is adopted, the nozzle area should be reduced below 66% of the bore area to balance the recoil completely without overbalancing it. On the other hand if a cover 98 is used over the perforations this in itself will cause a considerable increase in the backward recoil so that it may be-

come necessary to increase the nozzle area to a percentage exceeding the 66% of the bore area required for balancing the recoil of the barrel alone.

Figure 8 is a diagram illustrating a modified construction of gun wherein the cartridge chamber 2 is not coaxial with the gun at the rear end of the barrel, but is located at the side of the barrel. The figure shows the cartridge case 39 with the projectile 40 after it has travelled a short distance along the barrel from its loaded position just in front of the grid member 6. With this construction the breech cover 41 covers the ends of both the cartridge chamber 2 and the breech end of the barrel 4, and when the breech is opened the cartridge case 39 and the projectile 40 are loaded side by side into the gun.

In the case of the 1.9" gun illustrated by Figures 1 to 7, the cartridge case, which is generally of frustro-conical shape, has a relatively thick metal side wall but its ends are closed by thin walls, such as of metal foil, which are readily disrupted and/or consumed when the charge is ignited. Such end walls may be held in position and reinforced by end members comprising peripheral rings with a number of radial spider arms meeting centrally within the ring. In the case, however, of the modification illustrated by Figure 8, it is necessary for the side walls, instead of the ends of the cartridge case, to be readily disruptible and/or consumable, for which reason the cartridge case has relatively thick end walls and a cylindrical side wall of thin metal, or foil, reinforced and supported by spaced longitudinal supporting bars 42, as shown.

Figures 9 to 12 illustrate a construction suitable for a 3 1/2" low pressure gun for firing or projecting explosive bombs or like projectiles, and may be adapted for use as a shoulder fired weapon, or as a mortar.

In the case of a shoulder fired weapon the front portion of the gun may be substantially similar to that of the 1.9" rifle of Figures 1 to 7, and the breech portion is shown to a larger scale in Figure 9. In this case the breech block chamber 50 swings in a plane transverse to the bore of the gun, about an axis parallel to the barrel axis but laterally displaced therefrom. It is held in closed position by a locking pin 43, engaged in a hole 44 in a lug 45 on the wall of cartridge chamber 2, from which it can be withdrawn by a pivoted catch 46 operating against a spring 47, the catch 46 being pivoted in a handle 48 by which the breech block 50 is swung open and closed. When the catch 46 is operated it also moves, through suitable mechanism not shown in detail in the drawing, a slide 49 into a position locking or blocking the firing pin 51 against movement, the slide 49 being provided with an opening through which the firing pin may pass when the breech block is closed, but which is moved out of register with the firing pin upon operation of the catch 46.

The firing pin 51 is connected to a rocking lever 52 pressed by a spring 53 in a direction to pull the firing pin back. The breech block 50 is mounted on a sleeve 54 rotatable in bearings on the rear part of the gun barrel, and within the sleeve 54 slides a firing rod 55 the end of which carries a head 56 adapted to be engaged by the nose 57 of lever 58. A strong spring 59 in the sleeve 60, engaged behind a collar on rod 55, holds the head 56 of rod 55 up to nose 57 of the lever 58.

The lever 58 is rotatable on a pivot 61, and is normally tilted, so that its nose 57 engages head

56, by a spring 62. The free end of the lever 58 is articulated to the wire 13 leading to the 5 trigger mechanism, which may be similar to that 10 illustrated in Figure 1, or a suitable modification thereof. At about the middle of its length the 15 firing rod 55 is enlarged at 63 and carries a pair of radial pins 64 on which are mounted rollers 65. The forward end of sleeve 54 carries a spiral 20 cam 66 adapted to engage with rollers 65. The breech block 59 is keyed to sleeve 54, and the arrangement is such that when the breech block 25 50 is swung into closed position, the sleeve 54 is rotated and the spiral cam engages the rollers 65 and forces the firing rod 55 back, against the spring 59, until the nose of lever 58 engages under the head 56 and thus holds the firing rod in withdrawn or cocked position, ready for release by the trigger mechanism. When firing rod 55 is released its rear end strikes the end of rocking lever 52 and thus drives the firing pin 51 forwardly 30 into the percussion cap of the cartridge.

As before, the breech block 50 provides a space 3 between the cartridge and the gas discharge outlet or outlets, and contains the perforated grid member 6. The gas filling the interior of the breech block has free escape to the atmosphere through a ring of slightly diverging expansion nozzles 67, and through a central expansion nozzle 68. This nozzle 68 is adjustable so that the escape of part of the gases can be throttled by rotation in the bush 69, with which it has a screw thread engagement, so that rotation of the nozzle withdraws its inner end from its seating 90 to an extent determined by the rotation of nozzle 68. This extent can be measured by the indication of a pointer 91 reading on a scale ring 92 carried by the nozzle 68.

The extractor mechanism is illustrated by Figures 10, 11 and 12. The extractor comprises a pair of curved arms or levers 93 lodged in recesses in the wall of the cartridge chamber, the ends of which act on the ends of extractor pins 94 covered by the rim of the cartridge case. The lower ends of the arms 93 are rotatable on pivots and their hub portions carry diametrically opposite teeth or noses 95 which face in opposite directions. These noses 95 coat with projections or shoulders 96 on a pair of cams 97 integral with sleeve 54 and spaced apart to accommodate the lower ends of extractor levers 93 between them, with their planes at right angles to the planes of the levers. In consequence of this construction it follows that as sleeve 54 rotates with the breech block 59, as this is swung open, the shoulders 96 of cams 97 strike the noses 95 on extractor levers 93 and rotate both of said levers rearwardly, thus projecting the pins 94 outwardly and ejecting the cartridge case from the chamber.

The 3.45", 25 pounder gun illustrated by Figures 13 to 16 is mounted on wheels 70 and provided with the customary sighting equipment, and hand wheels 71, 72, for elevating and directing the barrel. It also carries a trail 73 to which the breech end of the gun may be bolted at 74 for transport purposes. The end of the trail 73 carrying a suitable coupling eye or hook 74a for towing purposes.

The gun in this case has a breech member 75 disposed between the grid chamber 76 and the gun barrel proper 77, which member is rotatable about vertical trunnions 79 midway along its length. The portions of the trunnions—shown in detail in Figure 16—which are engaged with the member 75 consist of bars 78, and the said bars are formed by two telescopic parts viz., a plunger

and an outer casing, with a spring 80 interposed between the parts as to make the bars 78 yielding as to their length, whereby a certain degree of longitudinal movement of the member 75 is permitted.

The breech member 75 is opened and closed by a handle 81 rotatable in brackets on the side of the member, and when the breech is closed the handle 81 occupies the position shown in dotted lines in Figure 14—i. e., pointing towards the rear end of the gun. On rotating the handle in a clockwise direction, its first movement rotates a small crank 82, and through a connecting rod 83, applies pressure to a locking pin 84 which bears on the end of the barrel. The consequent reaction shifts the member 75 rearwardly, which is permitted by the spring trunnion bars 78, thus causing positive disengagement of the member 75 from the gun bore. Further movement of the handle 81 carries the crank 82 past its dead centre position and withdraws the locking pin 84 from its hole in the end of the barrel, thus freeing the member 75 for rotary movement.

Continued movement of the handle 81 brings it up against a fixed abutment 85 (Figure 14) on the side of the member 75, whereupon this member rotates about its trunnions 79 into the position shown in full lines in Figure 14 and dotted lines in Figure 15.

During the initial rotation of the member 75 a cam 86 on the trunnion axis bears on the tail of the lever 87, and through rod 88 moves the pivoted extractor levers 89 through a small angle of 6°, thus loosening the cartridge case in the breech. As the member 75 swings into the fully open position the lever 87 strikes against a fixed stop 90, and the extractor is then moved a further 12° to throw the shell case out of the breech.

The grid chamber 76 of the gun is fitted with a ring of gas discharge nozzles similar to the 3.5" gun described with reference to Figures 9 to 12 and contains a perforated grid or cage of frustoconical form, as before, defining a space between the inlet ends of the nozzles and the chamber 45 space proper containing the propellant charge or cartridge.

This gun is intended to work with a high chamber pressure, in comparison with the 3.5" gun previously described which operates with a low 50 chamber pressure.

It will be understood from the foregoing that in non-recoil guns according to this invention, in order to produce a given muzzle velocity the propellant charge and therefore the cartridge chamber 55 of the gun must be considerably larger than in normal guns, in order to provide, in addition to the gases necessary to give the projectile the required muzzle velocity, the gases necessary to balance the recoil shock on the barrel of the gun.

As previously mentioned the propellant charge 60 may be made up of two separate charges one being of quick burning type and the other being of a slower burning type, the rate of burning of course depending, under equal pressure and temperature conditions, on the composition of the charge and its mechanical make-up, in well-known manner.

Various constructions of guns for carrying the invention into practice have been hereinbefore 70 described, but it should be understood that other constructions are possible within the scope of the invention. For example it is not essential for the gas chamber between the cartridge chamber and the rearwardly directed nozzles to be a co- 75 axial rearward extension of the barrel or for

said gas chamber to communicate with the cartridge chamber before firing. Thus a port may open into the gun barrel, which port is initially closed by the projectile, but as soon as the projectile commences moving, is placed into communication with the cartridge chamber space. The said port may communicate by a conduit or passage constituting a gas chamber separate from and substantially by the side of the cartridge chamber, with a rearwardly directed nozzle, which may be fitted with a control valve to control the rate of escape of the gases and thus the amount of the recoil absorbed. The chamber space proper of the gun is therefore enlarged by the initial movement of the projectile to include not only the volume enclosed between the cartridge and the base of the projectile, but also the volume of the gas chamber between the cartridge and the rear nozzle.

In view of the fact that the present invention may be embodied in guns having substantially different breech constructions, the term "breech chamber" has been used in the appended claims to mean that portion of the gun which includes both the space in which the cartridge is received when the gun is loaded and the gas space into which the propellant gases flow from the cartridge space through a substantially unrestricted venting area and from which they pass to the atmosphere through one or more discharge members of restricted area.

What I claim is:

1. A gun of the reduced recoil type comprising a barrel having a projectile-receiving portion at its rear end, a breech chamber including a cartridge space fixed to the rear end of the barrel in which an explosive propellant charge is received when the gun is loaded, the rear wall of the breech chamber supporting at least one rearwardly directed gas discharge member having a restricted inlet and an outlet open to the atmosphere, part of said breech chamber forward of the rear wall thereof and additional to the cartridge space forming a gas space of substantial volume in direct communication with both the cartridge space and the inlet of said gas discharge member, said cartridge space having a venting area into the gas space at least equal to the cross-sectional area of the barrel and said gas space being so constructed and arranged that

50

the gases developed by combustion of the propellant charge are free to expand therein when the charge is ignited, the cross-sectional area of the inlet of said gas discharge member being less than that of said barrel.

2. A gun according to claim 1 wherein the cartridge space is disposed laterally of the axis of the barrel.

3. A gun according to claim 1 wherein the gas space is coaxial with the cartridge space.

4. A gun according to claim 1 including a perforated screen in said gas space interposed between the inlet of said gas discharge member and the cartridge space.

5. A gun according to claim 4 wherein said perforated screen is of substantially conical form and has its larger end disposed over the inlet of the gas discharge member.

6. A gun according to claim 1 including an adjustable valve associated with said gas discharge member for regulating the effective cross-sectional area of the inlet thereof.

7. A gun according to claim 1 wherein said gas discharge member is in the form of an expanding gas nozzle.

CHARLES DENNISTOUN BURNETT.
